[57] CLAIM

The ornamental design for a handle for kitchen tools and gadgets, as shown and described.

DESCRIPTION

FIG. 1 is a perspective view of a handle for kitchen tools and gadgets, showing our new design;
FIG. 2 is a top plan view thereof;
FIG. 3 is a side elevational view of one side thereof;
FIG. 4 is a bottom plan view thereof;
FIG. 5 is a side elevational view of the other side thereof;
FIG. 6 is a rear elevational view thereof; and,
FIG. 7 is a front elevational view thereof.
The broken line showing of an upper portion of a fork in FIGS. 1 through 6 is for illustrative purposes only and forms no part of the claimed design.
